DESIGN FOR A LIGHTING UNIT

Carl F. Haas, Cleveland, Ohio, assignor to Westinghouse Electric and Manufacturing Company, East Pittsburgh, Pa., a corporation of Pennsylvania

Application October 30, 1936, Serial No. 65,606

Term of patent 14 years

To all whom it may concern:

Be it known that I, Carl F. Haas, a citizen of the United States, residing at Cleveland, in the county of Cuyahoga and State of Ohio, have invented a new, original, and ornamental Design for a Lighting Unit, of which the following is a specification, reference being had to the accompanying drawing, forming a part thereof. The single

figure is a side elevational view of a lighting unit embodying my new design. The opposite sides of the unit are substantially the same in appearance as the side disclosed.

I claim:

The ornamental design for a lighting unit substantially as shown and described.

CARL F. HAAS.
